UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed June 11, 1928. Serial No. 284,292.

My invention relates to a slicing machine and particularly to a slicing machine of a type having a rotary and preferably a motor driven knife. One object of my invention is to provide means for maintaining the knife clean. Another object is the prevention of the accumulation of grease and dirt within the knife housing. Another object is the provision of scraping or cleaning means which shall free the knife from grease developed by contact of the rapidly rotating knife with the hood. Another object is the provision of a knife of an improved contour or shape of blade. Other objects will appear from time to time in the course of the specification and claims.

I illustrate my invention more or less diagrammatically in the accompanying drawings, wherein—
 Figure 1 is a front elevation with parts broken away;
 Figure 2 is a rear elevation;
 Figure 3 is a section on the line 3—3 of Figure 1;
 Figure 4 is a section on the line 4—4 of Figure 2;
 Figure 5 is a section on the line 5—5 of Figure 1;
 Figure 6 is an elevation of the knife and guard assembly;
 Figure 7 is a detail of a grease receiving tray; and
 Figure 8 is a partial radial section through the knife, on an enlarged scale.

Like parts are indicated by like symbols throughout the specification and drawings. A generally indicates any suitable base upon which is mounted the motor A¹, the motor shaft A² and pulley A³ driving the belt A⁴. B indicates a guard plate lying in a generally vertical plane and M a gauge plate the details of guard and gauge plate forming of themselves no part of the present invention.

C indicates an upstanding portion of the frame positioned to the rear of the guard plate and forming, with its forward extension C¹, a closed housing in connection with the guard plate. It is provided with an extension C² which includes a generally cylindrical aperture C³ in which may be inserted a bearing sleeve D of the knife assembly hereinafter described. Mounted at each end of the sleeve are the ball bearing assemblies D¹ D² for the knife shaft D³, the knife shaft being provided with a reduced screw-threaded extension D⁴ which receives the lock nuts D⁵, whereby the shaft assembly is secured together, the inner race of the ball bearings D² abutting against a shoulder D⁶ of the knife shaft and being drawn thereagainst by the nuts D⁵. D⁷ indicates an enlarged end of the knife shaft to which is secured the pulley D⁸ adapted to receive the belt A⁴.

The knife proper generally indicated as E is secured to the knife shaft by the main securing bolt E¹ and by the bolts E² which pass through the enlargement D⁷ and into the pulley D⁸.

Positioned about the sleeve D is a bell deflector generally indicated as G such deflector including a hub portion G¹ about the sleeve D through which passes any suitable locking bolt or member G² for fixing the deflector in position in relation to the sleeve D.

The member C² terminates in a flange C¹⁰ which penetrates a recess G³ in the deflector G. G⁴ indicates the inner edge of the deflector, about such recess, which will be seen, in Figure 3, to overlap or overlie the inner edge C¹⁰ of the member C². G⁵ indicates a flange or extension at the opposite edge of the member G which extends into close proximity with the rear of the knife and entirely houses or encloses the pulley D⁸ and the belt A⁴. It will be understood that the parts are so shaped and proportioned that the deflector G and housing portions C, C¹

and C^2 completely enclose the knife shaft and the knife drive. The shape or cross-section of the periphery of the knife will be clear from Figures 3 and 8. The plane of the knife, as shown in Figure 3, is somewhat tilted in relation to the plane of the guard plate B, the axis of rotation of the knife being tilted slightly out of perpendicularity to the guard plate. The cutting plane or the plane of the cutting edge of the knife is inclined about three degrees from the plane of the guard plate or, more correctly, from the plane of the tracks K along which travels the meat carriage generally indicated as K^1 which will later be described in somewhat greater detail. The edge portion of the knife E is provided with a forward face E^5 and a rear face E^6 , the latter being shown as concave or hollow ground. The face E^5 may also be slightly concave. The curve of the knife so formed starts from the theoretical zero but the angle of the cutting edge portion at the point indicated at X in Figure 8 may be described as about six degrees. The hollow grinding or formation gives the knife a long, thin bevel.

The forward face of the knife is recessed as at E^{10} the corner or offset portion E^7 thus formed lying in the general plane of the guard plate B. The tilting or inclination of the knife serves to bring the cutting arc of the knife into the plane of the guard plate B, as shown in Figure 3, the rest of the knife being, of course, concealed or guarded by the guard plate and lying to the rear thereof.

The rear of the knife is recessed as at E^8 resulting in the offset portion or angle E^9 , clearly seen in Figures 3 and 10. This projecting portion E^9 overlaps or surrounds the flange or extension G^5 of the bell deflector G. It will be observed that the offset portions E^7 and E^9 are concentric but of different radius.

Figure 5 indicates the provision of scraping means for clearing the edge of the knife of particles of meat or other substances cut, or of lard or grease from the substance cut. Referring to Figure 5 E indicates the knife edge, and B^{10} the lower edge of the guard plate B. G^{15} indicates a downward projection from the bell deflector G. Secured to the member B^{10} is a spring blade generally indicated as H to the edge of which is secured a strip of more resilient material H^1 for example a razor blade. The member H is preferably but not necessarily of spring stock. It is mounted on the member B^{10} for example by the holding washer H^2 and the securing bolts H^3 . If necessary adjusting shims H^4 may be inserted. H^5 indicates a scraper member mounted on the portion G^{15} of the bell deflector and secured for example by the screws H^6 . It will be

realized that under some circumstances a scraper similar to the one shown on the opposite side of the knife may be employed also in the rear of the knife.

However, owing to the fact that the blade is hollow ground as at E^6 it is preferable to have the scraper H^5 formed as at H^7 to the contour of the knife face.

It will be clear from Figure 5 and from a comparison of Figures 1 and 2 that the opposed blades or scrapers are positioned adjacent the lowest point of the periphery of the knife and closely approach each other and preferably to a degree overlap. Note, with reference to Figure 4, that the knife or razor blade member H^1 depends a considerable distance below the edge of the knife, thus serving as a discharge member for dropping or depositing grease and small particles in the trough H^{10} which is positioned in the frame or base beneath the edge of the knife and the said scraper members and may be withdrawn for example by the handle H^{12} for cleaning. Note that the edges of the trough H^{10} are received in recesses H^{11} in order that there may be no space about the trough into which grease or fragments of material can penetrate. Also the lower edge of the member H^1 depends to a point beneath the upper edge of the walls of the trough H^{10} , thus limiting the discharge of material to the space within the trough and reducing to a minimum the tendency of the material discharged to reach any point outside of the interior of the trough. The result is a maximum efficiency of the cleaning action of the opposed scrapers and the reduction to a minimum of the tendency of grease and small fragments to be carried into the interior of the knife and transmission housing or space. Note, as on reference to Figures 1 and 2, that a recess H^{14} is provided in the frame, which recess overlies the open top of the tray H^{10} . The periphery of the knife closely approaches the top of the recess and the scraper H^1 penetrates the recess.

The work tray K^1 includes the plane horizontal portion K^2 and the upstanding edge portion K^3 lying along the edge of the member K^2 farthest from the knife when the carriage is in withdrawn position. As shown at the left of Figure 1 the inner edge of the carriage closely approaches the cutting arc of the knife and lies parallel with the path of movement of the carriage.

It will be realized that whereas I have described and shown a practical and operative device, nevertheless many changes might be made in size, shape, number and disposition of parts without departing from the spirit of my invention. I therefore wish my description and drawings to be taken as in a broad sense illustrative and

diagrammatic rather than as limiting me to my specific showing.

The use and operation of my invention are as follows:

5 In the employment of a motor driven knife one of the major difficulties is, owing to the relatively high speed of rotation of the knife, is the larding of the meat, when meat is being cut. If a piece of ham or bacon is sliced the extremely rapid movement of the travel of the knife through the bacon generates sufficient heat to hold a certain proportion of the grease from the bacon. This grease may drop to the base of the machine or may gather on the gauge plate or face plate or may be deposited or smeared on the face of the guard plate B. Also among many of the machines now on the market a very substantial proportion of this 15 grease adheres to the knife and is carried by the knife within the housing or space to the rear of the guard plate and is spattered or deposited therein. The result is an extremely unsanitary condition, as the 20 interior of the housing is inevitably hard to clean.

In applicant's device the amount of larding is greatly reduced and the deposit of grease and small particles within the housing is practically entirely eliminated. The hollow grinding of the knife provides a very thin blade at the point of initial contact or cutting operation and the resultant friction is substantially less, and therefore 30 the heat is less than when a blunt or more obtusely angled blade is employed. The result is an initial decrease of larding.

Finally the arc of the knife, the hollow ground or concave portion E⁶, tends to peel 40 or curl the slice away from the face of the knife, thus limiting the engagement of the slice with the rear of the knife and reducing friction of the slice against the knife.

Assuming that the deposit of particles on 45 the knife and the deposit of grease on the knife cannot be entirely eliminated, as is the case, the scrapers provided serve to remove from the knife substantially all of the grease and particles carried thereby. The forward 50 scraper H with its thin blade H¹, which is shown as inclined in relation to the radius of the knife, clear the flat face E⁵ of the knife. The inclination of the blade tends to carry 55 the grease and particles downwardly to the lower corner or edge of the plate, which lower corner lies within the hollow of the trough or drawer H¹⁰. The material from the opposite side of the knife is gathered 60 by the scraper H⁵, which conforms to the contour of the knife and which is positioned slightly in back of the scraper H, H¹. It does, however, depend below the edge of the knife and it, when taken in connection 65 with the opposite scraper, thoroughly cleans

this face of the knife, all the material so cleaned dropping in the drawer H¹⁰.

The space between the housing C and the guard plate B is thoroughly protected against access of material. Referring to the front 70 of the knife the guard plate B, sitting in the recess E⁶, gives thorough protection. As to the rear of the knife the offset portion E⁹ of the knife overlaps or extends outwardly beyond the edge G⁵ of the bell deflector G. 75 Also the inner edge G⁴ of the bell deflector extends outwardly beyond and overlaps the opposed flange C¹⁰ of the hub C² in which the knife bearing assembly is mounted. The hub C², however, is continuous with the 80 frame portion C, and a complete closure is thus provided.

The bell deflector G is automatically centered in relation to the knife and knife shaft, since it clamps about the exterior of the 85 bearing sleeve D, being held in position by any suitable screw or locking means G². The bell deflector is therefore inevitably concentric with knife and knife shaft and needs no separate adjustment. The knife assembly, including the knife shaft, the ball races D¹ D², the sleeve D and the bell deflector secured to the outside of it is inserted as a unit into the space C³ and is locked in position at the downward point for example by 90 any suitable locking screw or means C¹¹. The pulley D⁸ forms part of the same assembly and is housed between the knife and the bell deflector.

In employing the cutter the flat tray K² is 100 peculiarly efficient since it increases the capacity of the device and enables a whole loaf of bread to be decrusted or bacon rind to be cut off a whole block of bacon. The upright member K³ at the rear of the carriage prevents the formation of any rag or tail on the material being sliced.

It will be observed from Figure 3 that the hollow ground or exposed portion of the rear face of the knife and the bell deflector 110 G and the hub C² form, in horizontal axial cross-section, a generally concentric arc, or a continuous and more or less arcuate surface. These members entirely close the space to the rear of the knife and the slices, 115 as they are cut and curl from the back of the knife, cannot penetrate to the rear of the knife within the housing, and find no interrupting or interfering projection against which they abut, but drop freely to what- 120 ever receiving means are employed.

I claim:

1. In a slicing machine, a supporting frame, a rotary knife, a knife shaft therefor, a bearing sleeve about said shaft and 125 a guard mounted about said shaft and sleeve, the knife shaft, sleeve and guard being removable as a unit from the slicing machine frame.

2. In a slicing machine, a supporting 130

frame, a rotary knife, a knife shaft therefor, a drive pulley associated with said shaft, a bearing sleeve about said shaft, a guard member mounted about said shaft and sleeve and extending forwardly about said pulley and toward the rear face of the knife, the knife shaft, pulley, sleeve and guard being removable as a unit from the slicing machine frame.

10 Signed at Indianapolis, county of Marion and State of Indiana, this 5th day of June, 1925.

WILLIAM J. CAMPBELL.
